UNITED STATES PATENT OFFICE.

ROGER L. AVERY, OF CHICAGO, ILLINOIS.

SCHOOL FURNITURE.

Application filed July 20, 1921. Serial No. 486,167.

To all whom it may concern:

Be it known that I, ROGER L. AVERY, a citizen of the United States, and a resident of the city of Chicago, county of Cook and State of Illinois, have invented certain new and useful Improvements in School Furniture, of which the following is a specification.

My invention relates to improvements in school furniture, especially to a combination desk and seat, and has for its principal object the provision of an improved construction of this character which will be highly efficient in use.

A further object of my improved combination desk and seat is the provision to produce facilities whereby the desk and seat may be adjusted independently of each other, to accommodate pupils of different heights and sizes of bodies.

A further object of my improved combination desk and seat is the provision of an improved construction of this character which may be readily dismantled for shipping and readily mounted together by any person.

A further object of my improved combination desk and seat is the provision of a structure of this character which will withstand the rough usage applied by the pupil using the same and which will be economical in manufacture.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevational view of my improved combination desk and seat;

Fig. 2 is a fragmentary sectional detail view taken substantially on line 2-2 of Fig. 1;

Fig. 3 is a fragmentary sectional detail view taken substantially on line 3-3 of Fig. 5;

Fig. 4 is a front elevational view of the seat embodied in my combination desk and seat;

Fig. 5 is a front elevational view of the desk embodied in my improved combination desk and seat;

Fig. 6 is a fragmentary sectional detail view taken substantially on line 6-6 of Fig. 5;

Fig. 7 is a plan view taken substantially on line 7-7 of Fig. 1;

Fig. 8 is a fragmentary sectional detail view taken substantially on line 8-8 of Fig. 1;

Fig. 9 is a side elevational view of one of the hinge members embodied in my improved combination desk and seat; and

Fig. 10 is a perspective view of one of the hinge lock washers embodied in my improved combination desk and seat.

The preferred form of construction as illustrated in the drawings comprises a flange pedestal 15, in the shape of an I-beam, 70 secured to a base or floor plate 16 by means of a bolt 17 threaded in a socket 18 provided in one end of the said pedestal. The said pedestal 15 is held against revolving, should the nut of the bolt 17 work loose, by means 75 of a triangular shaped groove 19 provided in the top surface of the said pedestal, said grooves adapted to receive the bevelled ends 20 provided on the pedestal 15. A desk 20 is adjustably mounted on the pedestal 15 by 80 means of a pair of co-operating supporting members 22 and 23 having brackets 24 and 25 integrally formed thereon and secured to the under surface of the bottom of said desk by means of bolts or screws 26. Provided 85 on the inner faces of said supporting members 22 and 23 adjacent the end thereof are triangular shaped grooves 27 and 28 for the reception of the edges 29 of the pedestal 15 which are bevelled to correspond with the 90 triangular shaped grooves 27 and 28. A bolt 30 is positioned through each of the said supporting members adjacent the end thereof and provided with a nut 31 serving to rigidly hold said supporting members in 95 the desired adjusted position. Integrally formed on each of the said supporting members and extending laterally therefrom are bracing lugs 32 and 33 which serve as a brace member between the two supports. 100 The said lug 33 is provided with a notch 34 arranged for the reception of a tongue 35 provided on the lug 32. The lug 33 is provided also with a triangular shaped groove 36 arranged to receive the bevelled end 37 105 provided on the lug 32, said bevelled edge corresponding in shape with the groove 36. By providing lugs 32 and 33 as herein described, when adjusting the said supports in the desired position the said supports are 110 prevented against lateral or longitudinal movement with respect to each other.

Having thus far described the preferred form of construction of the desk and desk support, I will now describe the preferred form of construction of the seat and seat support which comprises a seat member 38 of any suitable construction, said seat member provided with a pair of hinge members 39 and 40 secured thereto by means of screws or any other suitable fastening means. Integrally formed on one end of the hinge members 39 and 40 are ears 41 and 42 arranged to register with ears 43 and 44 integrally formed on co-operating hinge members 45 and 46. The ears 43 and 44 are each provided with a central bore 47 for the reception of a boss or bearing 48 integrally formed on the inner surface of each of the ears 41 and 42. When said bosses are positioned through each of the bores 47, the surface of each of said bosses project beyond the inner surface of each of the ears 43 and 44. Formed on each of the bosses 48 are laterally extending lugs 49 arranged oppositely of each other and adapted to engage in recesses 50 formed in washers 51. The said washers 51 are positioned on the inner surface on each of the ears 43 and 44 and provided with a rectangular central bore 52 registering with bores 53 provided in each of the bosses 48, through which a bolt 54 is inserted serving to hold the said washers tightly against the surface of each of the said bosses or bearings 48. This arrangement is such that when mounting the hinge members together, by tightening each of the bolts 54 in position there will be no binding effect owing to the reason that the washers engage the surface of each of the bosses, thus permitting the hinge members a free pivotal movement. By providing the lugs 49 on the bosses 48, the said lugs engage the recesses 50 provided in the washers 51 which serves as a lock washer causing the bolts 54 to rotate with the pivotal movement of the hinge members, thus preventing the nuts of the said bolts from working loose. The corresponding inner surfaces of the hinge members 45 and 46, adjacent the ends thereof, are provided with grooves 55 for the reception of the edges 56 of the pedestal 15, said grooves and edges are similar in shape to that of the grooves 27 and 28 and edges 29, and arranged to serve the same purpose. The hinge members 45 and 46 are also provided with laterally extending interlocking spacing lugs 57 and 58 on their inner surfaces adjacent the ends thereof, said lugs being similar in construction to that of the lugs 32 and 33 and provided for the same purpose. A back rest 59, of any suitable construction, is supported by brackets 60 and 61 having their lower ends formed substantially at right angles and engaging the sides of the hinge members 45 and 46 and rigidly mounted thereon by

means of a bolt 67 passing through the said hinge members and said brackets serving to rigidly hold the seat member and back rest in the desired adjusted position.

I have also provided in the desk 21 a means for rigidly holding an ink bottle, preventing accidental spilling or knocking the same off the desk. This arrangement comprises a member 68 pivotally mounted on one side of the desk, said member provided with a leaf spring 69 adapted to engage the bottom surface of an ink bottle 70, holding the same rigidly against the under side of the top of the desk. The neck of the said ink bottle projects into a bore 71 provided through the top of the desk adjacent one corner thereof where ready access may be had to the said bottle.

By a construction of a combination school desk and seat as herein described it is to be noted that the back rest 59 and seat member 38 can be adjusted in any desired position, independently of the desk 21, by loosening the bolt 67 which permits a free longitudinal movement of the same. This arrangement is such that the seat can be adjusted to accommodate a small physically built pupil while the desk can be adjusted to accommodate a large physically built pupil, or vice versa. The construction of my improved combination desk and seat is such that the same can be readily dismantled, conveniently packed for shipment, and readily mounted together by any person.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:—

1. A school desk including a pedestal, and a desk support comprising co-operating parts in spaced relation with respect to each other and carrying interlocking spacing members, one of said spacing members having a groove formed in its side edge for the reception of the side edge of the other of said spaced members, substantially as described.

2. A school desk including a pedestal, adjustable supports and interlocking braces formed on the adjacent sides of said supports, one of said braces being provided with a groove formed in its side edge and extending longitudinally therewith for the reception of the adjacent side edge of the other of said braces, substantially as described.

3. In a school desk comprising in combi-

- nation with a support and a pair of co-operating desk supports carried by said support in spaced relation with respect to each other, of spacing members on the adjacent 5 sides of said desk supports, there being a recess formed in one of said members for the reception of a projection carried by the other of said members; substantially as described.
4. In a school desk, the combination of a 10 base; an I-shaped pedestal detachably mounted on said base; a pair of co-operating desk supports detachably mounted on said pedestal; a pair of co-operating seat supports detachably mounted on said pedestal; and interlocking means for retaining the pair of cooperating desk and seat supports in spaced relation with respect to each other, substantially as described.
5. A combination desk and seat, comprising in combination with a base, of a pedestal fixed to said base; seat supports embracing the side edges of said pedestal and adapted to be adjusted longitudinally with respect thereto; a back rest for said seat; brackets 25 carrying said back rest at one end and having their opposite ends bent substantially at right angles adapted to engage the sides of said seat supports; and a bolt passing through said bent ends and said support for 30 attaching said brackets to said supports and for securing said supports in the desired adjusted position, substantially as described.
6. In a school desk, the combination of a base; a pedestal rigidly mounted on said 35 base; a seat member adjustably mounted on said pedestal; a pair of co-operating desk supports mounted on said pedestal and adjustable longitudinally with respect thereto; bracing lugs formed on the inner sides of 40 said supports adjacent the end thereof and extending laterally therefrom; and a tongue formed on one of said lugs arranged to engage a recess formed in the other of said lugs, substantially as described.
- 45 7. A combination desk and seat comprising a base; a flange pedestal mounted on said base; a pair of co-operating seat supports mounted on said pedestal and adjustable longitudinally with respect thereto; a pair of co-operating desk supports mounted on said pedestal and adjustable longitudinally with respect thereto; and lugs integrally formed on the inner sides of said seat and desk supports, the inner edges of one 50 of said lugs provided with a groove for the reception of the inner edge of the other of said lugs, substantially as described.
8. A combination desk and seat comprising a base; a flange pedestal mounted on said 60 base; a pair of co-operating seat supports mounted on said pedestal and adjustable longitudinally with respect thereto; a pair of co-operating desk supports mounted on said pedestal and adjustable longitudinally with respect thereto; lugs integrally formed 65 with respect thereto; lugs integrally formed
- on the inner sides of said seat and desk supports, the inner edges of one of said lugs provided with a groove for the reception of the inner edge of the other of said lugs; and a tongue formed on one of said lugs adapted 70 to engage a recess in the other of said lugs, substantially as described.
9. A combination desk and seat comprising a base; a flange pedestal mounted on said base; a pair of co-operating seat supports 75 mounted on said pedestal and adjustable longitudinally with respect thereto; a pair of co-operating desk supports mounted on said pedestal and adjustable longitudinally with respect thereto; lugs integrally formed 80 on the inner sides of said seat and desk supports, the inner edges of one of said lugs provided with a groove for the reception of the inner edge of the other of said lugs; a tongue formed on one of said lugs adapted 85 to engage a recess in the other of said lugs; and a bolt positioned through said supports adjacent the ends thereof for rigidly securing said supports in the desired adjusted position, substantially as described. 90
10. In a combination desk and seat comprising in combination with a pedestal having oppositely disposed flanges, of a seat support carried by one of said flanges; a desk support carried by the other of said flanges, 95 said desk and said seat supports each comprising oppositely arranged parts in spaced relation with respect to each other; a back rest for said seat; supports for said back rest, the lower ends of said back rest supports being bent substantially at right angles 100 for engagement with the sides of said seat supports; and means for securing said back rest supports to said seat supports; and for securing said seat supports in position on the 105 flange of said pedestal, substantially as described.
11. A combination desk and seat comprising a base; a pedestal mounted on said base having bevelled side edges; a pair of co-operating seat supports mounted on said pedestal and adjustable longitudinally with respect thereto; bracing lugs integrally formed adjacent the ends of said seat support, the 110 end of one of said lugs provided with a groove for the reception of the end of the other of said lugs; a pair of co-operating desk supports mounted on said pedestal; and a vertically extending groove adjacent the 115 ends of said desk supports for the reception of said bevelled side edges of said pedestal, substantially as described.
12. A combination desk and seat comprising a base; a groove in said base; a pedestal rigidly mounted in said groove having bevelled side edges; a pair of co-operating seat supports mounted on said pedestal and adjustable longitudinally with respect thereto; a vertically extending groove adjacent the 120 end of said seat support for the reception of 125 said bevelled side edges of said pedestal, substantially as described.
- 130

said bevelled edges of said pedestal; a pair of co-operating desk supports mounted on said pedestal and adjustable longitudinally with respect thereto; vertically extending 5 grooves adjacent the ends of said desk support for the reception of said bevelled edges of said pedestal; and means for rigidly securing said seat and said desk supports in the desired adjusted position, substantially 10 as described.

13. A combination desk and seat comprising a base; a pedestal mounted on said base having bevelled side edges; a pair of co-operating seat supports embracing said pedestal; vertically extending grooves on the inner sides of said supports adjacent the end thereof for the reception of said bevelled edges of said pedestal; bracing lugs integrally formed on said desk supports, the end 15 of one of said lugs provided with a groove for the reception of the end of the other of said lugs; a pair of co-operating desk supports embracing the side edges of said pedestal; vertically extending grooves on the inner sides of said desk supports adjacent one 20 end thereof for the reception of said bevelled edges of said pedestal; and bracing lugs integrally formed on said desk supports, the end of one of said lugs provided 25 with a groove for the reception of the other of said lugs, substantially as described.

14. In a combination desk and seat, the combination of a base; a flanged pedestal having bevelled side edges mounted on 30 said base; a seat support embracing said pedestal; vertically extending grooves formed in said seat supports for the reception of 35

said bevelled edges of said pedestal; lugs formed on the inner sides of said seat supports and extending laterally therefrom; a tongue formed on one of said lugs adapted to engage a recess formed in the other of said lugs; a desk support embracing the said pedestal; vertically extending grooves in said desk support for the reception of said bevelled edges of said pedestal; lugs integrally formed on the inner sides of said desk support; and a tongue formed on one of said lugs and engaging a recess formed in the other of said lugs, substantially as described. 40 45

15. In a combination desk and seat, the combination of a base; a pedestal having bevelled edges mounted on said base, a seat support embracing said pedestal; vertically extending grooves in said seat supports for the reception of said bevelled edges of said pedestal; lugs formed on the inner sides of said seat supports and extending laterally therefrom; a tongue formed on one of said lugs and engaging a recess in the other of said lugs; a desk support embracing the said pedestal; vertically extending grooves in 50 55 said desk support for the reception of said bevelled edges of said pedestal; and brackets formed on one end of said desk supports and secured to the said desk, substantially as described.

In testimony whereof I have signed my name to this specification in the presence of two subscribing witnesses.

ROGER L. AVERY.
